FOUNTAIN INKWELL

Bert M. Morris, Los Angeles, Calif.

Application September 20, 1938, Serial No. 230,796

10 Claims. (Cl. 120—59)

My invention relates to that class of fountain inkwell used as a desk set and more particularly to that type which embodies a well-forming receptacle in which an inverted bottle of ink is received to act as a reservoir and supply ink to the well, with a pen normally reposing in a rest communicating with the well.

It is a purpose of my invention to provide a fountain inkwell of the type above described, 10 wherein means is provided for maintaining a predetermined level of ink within the well irrespective of temperature changes and even when the inkwell is jarred or suddenly moved, so that the possibility is eliminated of flooding the well to 15 conduct an excess amount of ink to the pen and thereby cause the nib to flood in writing and to contaminate the pen body with ink.

It also is a purpose of my invention to provide 20 a fountain ink well embodying a receptacle in which the conventional form of ink bottle may be received and replaced with a filled bottle when required.

A further purpose of my invention is the provision of a fountain inkwell which is characterized 25 by its structural simplicity, low cost of manufacture, and yet immune to the corrosive action of ink.

Another purpose of my invention is the provision 30 of a fountain inkwell in which the receptacle includes an inner bowl formed of glass or other non-corrosive material, and an outer container of a material, which although subject to the destructive action of ink is associated with the bowl so that at no time does ink come in 35 contact with the container but is retained at all times within the bowl.

Another purpose of my invention is the provision 40 of a fountain inkwell in which the receptacle includes a pen rest for holding the pen nib at a predetermined depth within the well, and characterized by having a tube, the wall of which is so constructed as to allow insertion and withdrawal of the pen without producing any pumping 45 action of the ink in the well and thus causing flooding thereof, and preventing the pen body from becoming contaminated with ink and soiling the fingers from the ink removed from the nib as a result of contacting with the wall of the tube.

Another purpose of my invention is the provision 50 of an ink bottle having an air and ink feeding plug which functions to regulate the ink discharged from the bottle in a manner to prevent flooding of the well in the event of the ink well being jarred or otherwise moved, and also

restricting discharge of ink from the bottle sufficiently to permit inversion of the bottle when placing it within the receptacle without spilling of ink on the exterior of the receptacle.

I will describe only one form of fountain inkwell 5 embodying my invention, including one form of bottle plug, and will then point out the novel features thereof in claims.

In the accompanying drawing:

Figure 1 is a view showing in central vertical section one form of fountain inkwell embodying my invention with a pen in position therein.

Fig. 2 is a horizontal sectional view taken on the line 2—2 of Fig. 1.

Fig. 3 is a vertical sectional view taken on the line 3—3 of Fig. 1.

Fig. 4 is a vertical sectional view taken on the line 4—4 of Fig. 1.

Fig. 5 is a sectional view taken on the line 5—5 of Fig. 1.

Fig. 6 is a detailed perspective view of the bottle plug shown in Fig. 1 on an enlarged scale.

Referring specifically to the drawing in which similar reference characters refer to similar parts in each of the several views, my invention comprises a receptacle including a container C having a base 15 which is rounded for a portion of its circumference and then tapered to a blunt point, as best illustrated in Fig. 2. The container also includes a tubular casing 16 which rises from the rounded portion of the base and is adapted to be molded integral therewith. A cover 17 of the same material as the casing is removably fitted on the upper end of the latter so as to close the same as will be understood.

The interior of the container is formed with a continuous shoulder 18 against which abuts the upper edge of a bowl B, adapted to be inserted into the base of the container and permanently secured in centered position therein against the shoulder, by the employment of a suitable plastic adhesive substance 19 which is also waterproof and ink resisting. As shown in Fig. 1, the side walls of the bowl are flared outwardly from the bottom to fit the shoulder 18 and to provide a V-shape gap between the confronting sides of the base and bowl. The substance 19 completely fills this gap to seal the bowl at the shoulder 18 and secure the bowl in fixed position within the base. This substance is adapted to be leveled off at the bottom of the container before it sets to provide a flat surface for a mat 20 preferably formed of sponge rubber to which it is glued to abut a shoulder 21 on the bottom edge of the base 15. This mat is provided for the purpose

of elevating the container base on the surface of a desk or other support to prevent marring thereof and to prevent slipping or skidding of the ink well as a unit, as will be understood. The 5 substance 19 gives the requisite additional weight to the receptacle to reduce the possibility of the ink well as a whole being accidentally tipped.

The bowl B is constructed of any suitable ink 10 resisting material such as glass, because the bowl constitutes the well of the invention and, consequently, is at all times in contact with the ink. The bowl bottom 22 is formed with a plurality 15 of ribs or beads 23 extending radially from a common center with their inner ends spaced one from the other. Between the inner bead ends the bowl bottom is formed with a groove G which extends approximately from the center defined by the beads to the bottom of the pointed end of the bowl. As shown the groove G is inclined 20 from end to end and formed with a narrow portion 24 which gradually widens into a broad portion 25. The portion 24 is defined by transversely rounded side walls 24a which merge into perpendicular walls 25a. The broad portion 25 and the walls 25a coact to form a well W, and the height of the walls 25a are increased to prevent overflow of ink therefrom by the provision of raised portions 27 on the bottom of the bowl.

The beads 23 provide means for supporting 30 an ink bottle 28 in inverted position within the casing 16, the casing serving to center the bottle so that its neck is centered with respect to the beads 23. The form of bottle here shown has a top shaped to provide an annular bead 29 and a 35 bottom bead 30. The internal diameter of the casing 16 and the cover 17 are such that the beads 29 and 30 are in contact therewith, thus providing a closed annular chamber 31 between the bottle and the casing and cover. This chamber provides a dead-air space which functions to insulate the bottle to such an extent that the air contained therein above the ink will be 40 responsive to sudden temperature changes. In this manner the possibility of the air in the bottle 45 above the ink changing in pressure and thus affecting the discharge of ink from the bottle, is reduced to a minimum.

The neck of the bottle 28 is shown as having 50 therein a plug 32 preferably formed of rubber to render it immune to the destructive action of ink. This plug is formed with an air inlet 55 passage 33 and an ink outlet passage 34. At the inner end of the passage 33 and at the outer end of the passage 34, restricted outlets 33a and 34a, respectively, are provided. The outlets function to regulate the ingress of air and the egress of ink in such a manner as to prevent the rapid flow of ink outwardly of the bottle even under 60 sudden temperature changes, or when the ink well as a whole is jarred or otherwise suddenly moved. The restricted outlets also so restrict discharge of ink from the bottle that it can be inverted and placed in the casing without ink discharging therefrom and spilling on the outer side 65 of the receptacle.

To limit movement of the plug 28 inwardly of the bottle neck, and, also, to fill the groove between the rounded edge of the bottle neck and the plug thereby precluding an air pocket within 70 the groove, the plug is formed at its outer edge with a flange 32a.

With the bottle and plug in position within the receptacle, as illustrated in Fig. 1, the passages 33 and 34 are positioned between the inner 75 ends of the beads 23 and directly over the ad-

jacent end of the groove G. From the passage 34 ink is discharged into the narrow groove portion 24 through which it flows into the well W. Due to the contour of the groove filling of the well with ink to the proper level is assured before 5 the air passage 33 is cut off by the ink against the admittance of further air into the bottle. This is true during the initial supply of ink to the well and as well as during all subsequent ink supplying operations resultant of dipping a pen into 10 the well.

By reason of the contour of the groove G a body of ink is supplied to the well W having a greater surface area than that within the narrow portion 24. The result is that due to the natural 15 cohesion of the ink molecules the ink in the well tends to draw into the well the ink contained in the groove portion 24. This drawing action is sufficient to overcome the tendency of the ink to adhere to the exterior surfaces of the bottle 20 neck and plug, and thus the proper flow of ink to fill and refill the well is assured.

The aforescribed functions of the plug outlets and the groove G of the bowl all contribute to the common end of maintaining in the well 25 25 a constant level of ink and one which never rises above the bottom of the plug 32, or overflows from the well, or supplies an excess amount of ink to the nib of the pen reposing in a pen rest, which latter will now be described.

The tapered end of the container C is constructed to provide a pen rest R disposed at an acute angle to the casing 16 and leading into the bowl B, so that the nib N of a pen P inserted thereinto will repose within the ink contained in the well 25. This pen rest R is in the form of a tube cast integral with the container and shaped interiorly to form an annular shoulder 35 against which seats the enlarged portion 36 of the pen.

The base of the pen rest tube is, as best shown in Fig. 5, formed with an annular series of longitudinal extending ribs 37 each of which has a rounded edge, while the intervening groove 38 between any two adjacent ribs is U-shape in cross section. This construction provides the following advantages. It provides vents for air to be admitted to the bowl and thence to the bottle, and permits insertion and withdrawal of the pen without producing any pumping action 60 of the ink to cause flooding of the well. Also, because of the rounded edges of the ribs the nib as withdrawn or inserted into the pen rest will be guided into any one of the grooves between the ribs, and in this manner ink is prevented 65 from accumulating on the exposed edges of the ribs to be deposited on the pen body and thus soil the fingers of the writer.

Although I have herein shown and described only one form of fountain inkwell embodying my 60 invention, it is to be understood that various changes and modifications may be made herein without departing from the spirit of my invention and the spirit and scope of the appended claims.

I claim:

1. A fountain inkwell, comprising; a bottle receptacle having a container and bowl within the container, the container comprising a hollow base having a circular portion with an integral casing rising therefrom and a tapered portion extending radially from the circular portion, said portions having a continuous shoulder interiorly thereof, said bowl of the same general shape as said base and formed of an ink resisting material with its upper edge of the same contour as

and abutting said shoulder, said bowl having a well in the bottom of the tapered portion and provided with a groove for conducting ink into the well, said groove inclined toward and widening into the well, a pen rest in the container communicating with the well, and means for securing the bowl within the container with its upper edge abutting said shoulder.

2. A fountain inkwell, comprising a container having a casing in which an inverted bottle of ink is adapted to be received, and a pen rest disposed to one side of said casing; a bowl within the container having beads upon which the neck of a bottle within the casing is adapted to be supported, said bowl being formed with a well directly beneath the pen rest, and having an inclined groove in its bottom extending from between said beads to said well, and widening as it approaches the well.

20 3. A fountain inkwell, comprising; a container formed of a composition material, having a casing in which an inverted bottle of ink is adapted to be received, a cover for closing the casing at the top thereof, and a pen rest at one 25 side of the casing having grooves therein for admitting air to the container even when a pen is reposing in the pen rest; a bowl within the container and sealing the joint between the bowl and container; said bowl having a well therein 30 directly beneath the pen rest, means in the bottom of the bowl for supporting an inverted bottle in elevated position within the bowl, and a groove in the bowl extending from said supporting means to said well for supplying ink from 35 the bottle to the well.

4. As an article of manufacture, a plug for ink bottles comprising a body adapted to fit within the neck of a bottle and formed with an air passage and an ink passage, the outlet ends 40 of said passages being constricted to restrict the flow of air and ink, respectively, therethrough.

5. A fountain inkwell, comprising; a container 45 formed of composition material, having a hollow base, a casing rising from the base in which an inverted bottle of ink is adapted to be received, and a pen rest in the base at one side of the casing; a glass bowl within the base having side walls which diverge from the bottom upwardly; a body of plastic material between the bowl and said base for securing the bowl within the base and giving such weight to the base as to preclude tipping of the inkwell; said bowl having a well therein directly beneath the pen rest, means in the bowl bottom for supporting a bottle within the casing in elevated 55 position with respect to the bottom of the bowl, and an inclined groove in the bowl bottom extending from said means to the well.

6. A fountain inkwell, comprising; a container having a casing in which an inverted bottle of ink is adapted to be received, and a pen rest disposed to one side of said casing; a bowl within the container having beads upon which the neck 5 of a bottle within the casing is adapted to be supported, said bowl being formed with a well disposed to one side of said beads and directly beneath the pen rest, and having a groove in its bottom extending from between said beads 10 to said well for conducting ink from the bottle to the well, wherein the beads extend radially from a common center and are spaced from the center, and said groove extends from said center to said well.

7. A fountain inkwell as embodied in claim 5, wherein a mat of sponge rubber is secured within the base beneath said body to cover the latter and project from the base to form a non-skidding support for the container.

8. As an article of manufacture, a plug for ink bottles comprising a body adapted to fit within the neck of a bottle and formed with an air passage and an ink passage, the outlet ends of which said passages being constricted to restrict the flow of air and ink therethrough, and an annular flange on the outer edge of the plug adapted to fill the groove between the plug and the edge of the bottle when the plug is within the neck.

9. In a fountain inkwell, a tubular casing reduced in diameter between its ends to define a relatively large bowl containing portion and an ink bottle-containing portion formed integral with the bowl containing portion, the reduction 35 of said casing defining a continuous shoulder around the interior of the casing, a bowl in said bowl containing portion and provided with side walls the upper edges of which abut said shoulder, a pen rest on one side of said casing extending into the bowl, and means for supporting the open end of an ink bottle over the bowl, said bowl having a well formed in the bottom beneath said pen rest.

10. In a fountain inkwell, a casing in which 45 an inverted bottle of ink may be placed, a pen rest disposed to one side of said casing, and a bowl adapted to receive ink from the bottle in said casing, said bowl having a well formed in the bottom to one side of the center thereof directly under said pen rest, and also provided in said bottom with a groove inclined from a point which is directly beneath said bottle, to said well and widening as it approaches said well.

BERT M. MORRIS.
